(57) **CLAIM**

The ornamental design for a tank assembly for fire suppression, as shown and described.

DESCRIPTION

FIG. 1 is a perspective view of a tank assembly for fire suppression, showing my new design;

FIG. 2 is a front elevation view;

FIG. 3 is left side elevation view;

FIG. 4 is a right side elevation view;

FIG. 5 is a top elevation view; and,

FIG. 6 is a bottom elevation view.

The broken lines shown in the drawings depict portions of the tank assembly for fire suppression that form no part of the claimed design.
